METAL AWNING

Frank F. Whiteside, Jacksonville, Fla.

Application September 30, 1947, Serial No. 777,010

5 Claims. (Cl. 20—57.5)

1

This invention is directed to ventilating weather protecting structures and in particular to metal awnings.

In the construction of metal awnings, it is endeavored to achieve shade by obscuring the rays of the sun, to provide a shelter from rain, and at the same time, to permit air circulation for ventilation. The latter requires openings for the passage of air currents through the awning and this is repugnant to the water-proof characteristics of a roof. Many suggested solutions have been made for forming protected openings in an awning, but all seem to fail when a substantial quantity of water falls on the awning during a heavy rain storm, and especially when the rain is accompanied by a high wind which drives the water through the openings formed in the awning for the purpose of ventilation.

An object of this invention is to construct an awning which will permit the passage of air therethrough, and at the same time will prevent the passage of water through the roof even if the same is in the form of a rain driven by a high wind. Further objects of the invention are to construct a weather protecting structure which may be in the form of sheathing, siding, metal tiles, or shingles.

Generally, these are obtained by constructing a covering composed of lapped sheets of metal, the overlapped portions being connected by a member which is provided with ventilating openings protected against the passage of rain water therethrough. The edges of the sheets are formed to provide drip edges and gutterways and the ventilating openings are protected by depending flanges so that the water falling on the covering is disposed of in one way or another without passing through the ventilating openings.

The means by which the objects of the invention are obtained are more fully described with reference to the accompanying drawings in which:

Fig. 1 is a perspective view of an awning constructed according to this invention;

Fig. 2 is a perspective view of an interior corner construction of the awning;

Fig. 3 is an enlarged perspective view, with portions broken away, of a portion of the awning;

Fig. 4 is a cross-sectional view of the sheet shown in Fig. 3;

Fig. 5 is a cross-sectional view on the line 5—5 of Fig. 4;

Fig. 6 is a cross-sectional view on the line 6—6 of Fig. 4;

Fig. 7 is a cross-sectional view similar to Fig. 6,

2

but showing a modified form of the invention; and

Fig. 8 is a cross-sectional view of a further modified form of the invention.

5 The assembled awning, as appearing in Fig. 1, consists of a top panel A and side panels B connected by a frame C composed of angle irons screwed or bolted to the top and side panels. A decorative border D may be attached to the lower edge of the awning. The panels A and B are of similar form, the panel B being cut to a triangular shape.

Preferably, the panels are made of a light gauge sheet metal. A flat metal sheet is folded 15 and rebent upon itself to form courses 2, the overlapped courses giving the sheet a clapboard appearance. These courses are connected by members 4 extending from the lower forward edge 6 of one course to the upper and back edge 15 of the underneath course. In bending the sheet to form the member 4, the edge 6 is made rather sharp in order to form a drip edge for water draining down from the plane of a course 2, while the upper edge 8 is given a comparatively 25 large radius to form a roll back for water which may be blown by the wind beneath the lapping courses. Member 4 is inclined between the upper and lower courses, and forms a relatively sharp angle with the upper course, and a relatively larger angle with the lower course.

Member 4 contains a number of ventilating openings 10, each of these openings being surrounded by a depending flange 12. Openings 10 are spaced from the front and back edges of 35 member 4. Flanges 12 may be extruded from the material adjacent the openings 10 or may be separately formed and attached to the circumference of the opening. In any event, the flange descends from the lower surface of member 4 a sufficient distance to prevent a direct entrance 40 of water through openings 10. Consequently the depth of flange 12 depends upon the inclination of member 4 and the diameter of opening 10. As seen in Figures 3 and 4, water being blown 45 parallel to the upper surface of a course 2 cannot pass directly through an opening 10. In Figures 3 to 6, these openings are shown to be circular, but they may be elliptical openings 10a surrounded by elliptical flanges 12a, as indicated in 50 Figure 7. Flanges 12 in Figure 4 are perpendicular to the plane of member 4. However, the outward portion on the flange on the weather side of the opening is the one which essentially provides a barrier against the passage of water through the opening, and this portion of the

flange may be elongated as shown by the flange 12b in Figure 8. In this case flange 12b extends at other than a right angle to the plane of member 4, and as shown in Figure 8, extends vertically.

The metal sheet constructed as above described functions very effectively as a protection against rain, while at the same time it provides adequate ventilation. As water falls on the courses 2, it drains downwardly over the edges 6, each edge by being fairly sharp having a tendency to cause drops of water to break off and fall on the lower course instead of rolling around the edge and down on the lower face of member 4. Any water which does drain around onto the lower face of member 4 is stopped from entering the openings 10 by the protecting flanges 12, and water collecting on the lower relatively sharp edges of flanges 12 will readily drop off and drain down onto the lower course. Consequently, incidental drainage will not pass through openings 12 to the underside of the awning.

When rain is being driven by a wind, drops of water are blown off edge 6 and the lower edge of flanges 12, but are prevented from passing through the openings 10 by flanges 12, and instead are driven against the curved edge 8, where the water collects and drains down the surface of the lower course. Because the flange 12 surrounds each opening 10, the opening is protected against the passage of water no matter from which direction the wind blows. If, during violent gusts of rain, some water piles up beneath flange 4 and is sprayed through the openings 10, the same for the most part will collect on the under surface of the upper course 2 and drain down into the gutter formed on the inside of lower edge 6, and from there drain into the sides of the awning where it will drip to the ground. In any event, substantially no water, or even a mist, will appear beneath the awning during a violent tropical storm.

The entrance of water through the openings 10 is further prevented by the fact that while it is raining the air beneath the awning is hotter, and lighter than, the air being cooled by the rain. Consequently, there is normally a passage of air from beneath the awning up and outwardly through the openings 10, this current of air being opposed to the currents of air which would drive water from the outside through the awning.

A further feature of the awning lies in the fact that a substantial amount of light passes through openings 10 if the awning is made of a light reflecting material, or painted with a light reflecting material such as a white paint. No matter from which angle light comes, it is reflected from the upper surface of a course 2 through the openings 10 and then reflected to below the awning from the under surface of each course 2 respectively. While no measurements have been made of the amount of light reflected through awnings constructed according to this invention thus are illuminated on their under surfaces by light reflected from the outside, and provide a fairly bright overhead covering.

The awning satisfies a long sought need for a

covering which provides ventilation as well as shelter from the elements. When constructed of a weather enduring material, such as aluminum, it requires no maintenance. During hard-driving tropical storms, where the rain is blown almost horizontally, and as the wind shifts and strikes the awning from every direction, scarcely a discernible mist appears beneath the awning. At the same time, the hot air collected beneath is exhausted through the awning. This ventilation also takes place during dry spells and during light rains, thus providing shade and comfort to all those who have sought its shelter. As indicated by the vertical position of side panels B, the invention is also useful as siding or sheathing for buildings. Furthermore small units can be made in the form of metal tiles or shingles.

Having now described the means by which the objects of the invention are obtained,

I claim:

1. A ventilating weather protecting structure comprising a plurality of longitudinally elongated flat course members, the lower marginal edge portion of one course member overlapping and being spaced from the upper marginal portion of an adjacent course member to form a drip edge, a connecting member inclined between the lower marginal edge of the upper course member and the upper marginal edge of the lower course member, said connecting member being integral with said upper and lower edges and joined thereto by acute angle folds in the material forming said members, a plurality of apertures in said connecting member, each aperture being spaced from said upper and lower edges, and a flange depending from the periphery of each aperture a distance such that a line lying in a plane parallel to the surface of the lower course member and tangent to the lower edge of said flange will not pass through said aperture.

2. A ventilating structure as in claim 1, said connecting member comprising a flat planar member extending between said upper and lower edges.

3. A ventilating structure as in claim 2, said lower marginal portion of the upper course member lapping approximately one-fourth of the lower course member.

4. A ventilating structure as in claim 1, said apertures being of circular shape.

5. A ventilating structure as in claim 1, said apertures being elliptical in shape with the major axis of the opening paralleling said lower edge.
